UNITED STATES PATENT OFFICE.

THOMAS R. COOK AND DONALD N. SMITH, OF SCRANTON, PENNSYLVANIA, ASSIGNEES
TO THE HUDSON COAL COMPANY, OF SCRANTON, PENNSYLVANIA.

SAFETY MINE HOIST.

Application filed April 21, 1927. Serial No. 185,603.

An extensively used type of mine hoist, embodying a safety mechanism known as the "Royer overwind", is provided with automatic means to prevent excessive speed of the hoist either when hoisting coal or when hoisting men, and embodies automatic means to prevent travel of the hoist past the coal landing when hoisting coal, or past the man landing when hoisting men. These means embody:—first, a control member active to both close the throttle of the hoisting engine and apply brakes, second, an actuator for said control member, and third, a ball governor for moving said actuator toward said control member proportionately with increase of the hoist speed. The actuator strikes and operates the control member when the two are relatively moved sufficiently to permit, and such operation of the control member effects throttle closing and brake application. The operation of parts is unerring when the hoist is operating at coal speed and often when moving more slowly for hoisting men, but if the man speed is slower than a predetermined speed as the cage nears the man landing (which reduced speed may still be a dangerous speed at which to land the cage on the fans), the governor balls do not move sufficiently under centrifugal force, to shift the actuator into co-operative relation with the control member and hence automatic slowing down of the cage cannot be effected, although overwind will be prevented in the usual way. It is the primary object of our invention to overcome this objection by the provision of means, independent of the ball governor, for positively moving the actuator toward the control member to a predetermined position, as near-landing movement of the hoist takes place, and said position is such that striking of the control member by the actuator is insured, should the engineer fail to slow the hoist at the man landing. Thus, under such circumstances the hoist would be automatically brought to a stand-still, even if the governor were rotating too slowly to have effected the hoist-stopping operation.

In operating hoists of the above defined character, when men are to be hoisted, the cage loader signals to the engineer that the next load will be men. The engineer returns signals his understanding to the cage loader and is supposed to condition the hoist for

man speed. Then, upon loading of the cage, 55 the cage loader signals for the engineer to start the hoisting operation, but it sometimes happens that the engineer fails to condition the hoist for man speed, placing the occupants in jeopardy. It is a further aim of 60 our invention to prevent this, by placing the man-speed conditioning means and the engineer's signalling means under a common control. Thus, as he signals to the cage loader his understanding that men are to 65 be hoisted, he is constrained to condition the hoist for relatively slow speed and for stopping at the man landing.

With the foregoing in view, the invention resides in the novel subject matter hereinafter described and claimed, the description being supplemented by the accompanying drawings.

Fig. 1 is a front elevation illustrating the "Royer overwind" improved in accordance 75 with our invention, parts being in section.

Fig. 1 is a vertical sectional view substantially on line 2—2 of Fig. 1.

Fig. 3 is a fragmentary horizontal section, partly broken away, taken approximately 80 on line 3—3 of Fig. 2.

Fig. 4 is an elevation partly in section, similar to a portion of Fig. 2 but showing a different position of parts.

In the drawings above briefly described, 85 the numerals 5 designate two vertical stands which support a pair of horizontally disposed, rotatable tables 6. Worms such as 7 of Fig. 2, engage worm teeth at the peripheries of the tables 6 and are carried by transverse shafts 8. By appropriate gearing 9, these shafts are connected with a pair of drive shafts 10 having sprockets 11, these sprockets being adapted for connection by chains with the usual sprockets of the hoisting engine. One of these last named 90 sprockets is secured against movement with respect to its carrying shaft and the drum keyed to the shaft. This sprocket may be keyed to the shaft or bolted to the keyed 100 drum, the effect will be the same. For the clutched drum, the sprocket must be preferably bolted to the drum or other suitable connection to the drum made, such, that the rotation of the sprocket conforms to the 105 loose or clutched drum. Any slippage of the shafts 8 and associated parts with respect to each other, gives an alarm, through

the instrumentality of a slip-indicating switch 42 (Fig. 1) forming no part of the present invention.

Each stand 5 carries a control member 13 for the hoist, said member being connected with the upper end of a shaft 14. This shaft and control member form parts of the customary mechanism for automatically closing the throttle of the hoisting engine and applying brakes, when said member 13 is horizontally turned. 15 denotes a rotary actuator for the control member 13, said actuator being commonly in the form of a pin disk, whose pin 16 is adapted to strike the control member 13 and turn it horizontally, under certain conditions. One of these actuators 15 is of course provided for each of the control members 13, and for moving these actuators toward the control member 13, proportionately with hoist speed increase, two ball governors 17 are provided, driven by appropriate gearing 18 from the shafts 10. Whenever the hoist runs at a sufficiently excessive speed to cause either 25 governor 17 to lower the corresponding actuator 15 sufficiently to cause its pin 16 to strike the subjacent control member 13, the latter is turned, automatically closing the throttle of the hoisting engine and applying the brakes.

Means are provided, embodying the tables 6, for raising the control members 13 and causing actuation thereof by the actuators 15, in case the engineer should fail to stop 35 the hoist at the predetermined landing. Levers 19 are disposed one above each table 6 and are fulcrumed at one end to stationary posts 20 at the centers of said tables, while the other ends of these levers are suitably 40 connected at 21 with the control members 13. Each of these levers carries a shoe 22 commonly known as a "coal speed dog", and the tables 6 are each provided with a "coal speed cam" 23 for co-operation with the "coal 45 speed dog". In case the engineer does not take steps to stop the hoist at the predetermined coal landing, cam 23 engages the dog or shoe 22, thereby swinging the lever 19 upwardly and disposing the control member 50 13 in the path of the pin 16 on the actuator 15. Thus, the pin strikes the control member and turns it, thereby stopping the engine and applying the brakes.

Pivottally mounted upon each lever 19, is 55 a second shoe or "man speed dog" 24, and when the hoist is set for hoisting coal, these two dogs or shoes 24 are swung upwardly to some extent as indicated in Fig. 1, said dogs or shoes then being disposed above cams 25 which are provided on the tables 6 for their actuation. The cams 25 are somewhat higher than the cams 23 and when the dogs or shoes 24 are swung downwardly to the position of Fig. 4, said dogs or shoes are 60 positioned in the paths of the cams 25. This

downward swinging of the dogs or shoes 24 is effected when men are to be hoisted instead of coal. Thus, if the engineer does not take steps to stop the hoist as the man landing is neared, the cam 25 will engage and 70 raise the shoe or dog 24, thus correspondingly raising the lever 19. This raising movement of the lever 19 is greater than that which is imparted to it by the cam 23 and the shoe or "coal speed dog" 22, and 75 hence said lever 19 will raise the control member 13 to a greater extent than the latter could be raised by said parts 22 and 23. Thus, if the hoist be running at a sufficiently great speed, the pin 16 of the actuator 15 80 will strike the control member 13 as soon as the latter is raised by the lever 19, the shoe 24 and the cam 25. However, it often happens that when approaching the man landing, the hoist is being run so slowly that the 85 governors 17 cannot act to downwardly force the actuators 15 sufficiently to bring their pins 16 into co-operative relation with the control members 13. Nevertheless, even this reduced speed may be such as to make 90 the landing of the cage on the usual fans, an operation hazardous to the cage occupants. Due to the nature of our invention however, the cage running at or near the reduced speed just referred to, will have its 95 travel automatically checked, forcing the hoist operator to take proper steps for landing gently upon the fans.

Overwind of the hoist is prevented by the portion 25 of cam 25. If the cage starts 100 past the man landing, this cam portion effects raising of the control member 13 into the path of pin 16 and cage stopping is effected.

Disposed above each table 6, is a second 105 lever 26 having operative connection at 27 with a collar 28 which rests on the actuator 15. A post 29 suitably secured to the stand 5, is provided for each of the levers 26, and these levers are fulcrumed to the posts as indicated at 30. Each lever 26 is provided 110 with means, such as the weight 31 for urging it in a downward direction, to depress the associated actuator 15 to a predetermined position, at which position the actuator pin 16 must necessarily strike the control member 13, when raising of the latter is effected by engagement of cam 25 with shoe 24. Means however, are provided for holding 115 the lever 26 against action under the influence of the weight 31, during the greater part of the hoist travel. This means embodies a post 32 appropriately connected at 33 with the lever 26, a roller or other suitable shoe 34 on the lower end of said post, and an arcuate track 35 carried by the table 6 for co-action with said shoe 34.

When operating at coal speed, the lever 26 is so supported that the shoe 24 is then 120 clear of the track 35. However, provision 125

is made whereby upon lowering of the "man speed dog" or shoe 24 into the path of the cam 25 to set the hoist for carrying men, the lever 26 is lowered sufficiently to place its shoe 34 in co-operative relation with the track 35. In this connection, it may be explained that the "coal speed" setting of the mechanism is shown in Fig. 2, whereas the "man speed" setting thereof is disclosed in

10 Fig. 4.

When the lever 26 is in the position of Fig. 4, its sole supporting means is constituted by the post 32, the shoe 34 and the track 35, and during the greater part of the hoist travel, while hoisting the men, this supporting means holds said lever 26 against action under the influence of the weight 31. However, when the hoist reaches a near-landing position, the track 35 clears the shoe 34 and the weight 31 then immediately comes into play to swing the lever 26 downwardly beyond the position shown in Fig. 4. Hence, this lever pulls the actuator 15 downwardly irrespective of the action of the associated governor 17, and places said actuator rather close to the subjacent control member 13. Now, in case of any speed of the hoist sufficiently great to still further lower the actuator 15, it will strike the control member 13, closing the throttle and applying the brakes. Moreover, should the engineer fail to take steps to stop the hoist at the man landing, the cam 25 will raise the shoe 24 and the lever 19, thus moving the control member 13 immediately into the path of the pin 16, so that said pin will strike said control member and bring the hoist to a standstill. It will thus be seen that even though the hoist be moving at such a slow speed as to prevent the ball governor 17 from depressing the actuator 15 into co-operative relation with the control member 13, when near-landing movement of the hoist takes place, the lever 26 and associated parts will effect such depression and insure proper automatic cut-off under circumstances requiring such stopping of the hoist.

In the present showing, a brace link 36 is provided for each post 32, and each of these links is pivoted to a post 37 suitably carried by a part of the stand 5.

Rockably mounted above the tables 6, is a shaft 38, the bearings 39 of this shaft being preferably secured to a horizontal bar 40, the latter being in turn secured to the usual posts 41 which support the dial 42, the latter being of customary construction and co-operating in the usual way with the cage travel pointers 43. The shaft 38 is provided with two crank arms 44 which are connected by links 45 with other crank arms 46 on shafts 47 which carry the shoes or "man speed dogs" 24. The shaft 38 is also provided with a crank arm 48 to which a rod 49 is connected. The arms 44 and the

arm 48, together with the shaft 38, constitute bell cranks for operating the links 45.

Suspending links 50 are provided for the two levers 26, the upper ends of these links being pivoted to the arms 44, while the lower ends of said links have pin and slot connections 51 with said levers 26. When the hoist is set for handling coal, as seen in full lines in Fig. 2, the links 50 support both levers 26, their shoes 34 being then a trifle above the tracks 35. However, when rod 49 is moved to effect actuation of the links 45 for the purpose of lowering the shoes or "man speed dogs" 24, conditioning the hoist for handling men instead of coal, the links 50 immediately free the levers 26 as will be clear from Fig. 4. Thus, these levers may act under the influence of the weights 31, to effect lowering of the actuators 15, when the near-landing movement of the hoist takes place, as previously described.

A bell crank 52 which may well be appropriately mounted upon one of the posts 41, is connected with the lower end of the rod 49, and by means of a rod 53, this bell crank 52 is connected with another bell crank 54. This bell crank 54 is connected by a rod 55 with an engineer's control lever 55 which may be set at either coal speed position or man speed position and may be held at the proper setting by means of an appropriate dog 56 and segment 57. When lever 55 is in the full line position of Fig. 2, setting of the hoist for handling coal is effected, but movement of said lever to the dotted line position of Fig. 2, immediately conditions the entire mechanism for hoisting men.

When men are to be hoisted, the cage loader signals this fact to the engineer. Then, the engineer is supposed to return signal to the cage loader that he understands that men are to be hoisted, and he is then supposed to set the hoist for man speed.

With the ordinary types of safety hoists, however, the engineer sometimes inadvertently fails to set the mechanism for hoisting men and hence the lives of the cage occupants are placed in jeopardy. Our invention however, provides means whereby such an occurrence cannot happen, as provision is made whereby operation of the lever 55 simultaneously sets the mechanism for hoisting men and signals to the cage loader, the engineer's understanding of the fact that men are to be handled.

In the present embodiment of the invention, we have shown a signalling switch 58 connected by a link 59 with the bell crank 54, said switch forming part of the engineer's signalling means to the cage loader. The signal proper is diagrammatically shown at 60, wiring 61 is indicated between the switch and the signal, and 62 designates a battery in said wiring. When lever 55 is set at coal speed position (full lines Fig. 2), the switch 58 remains

95

100

110

115

120

125

130

open. However, when the cage loader signals to the engineer that men are to be hoisted, the engineer moves the lever 55 to the dotted line position of Fig. 2, and in so doing, he not only operates the switch 58 to return-signal to the cage loader, but he simultaneously actuates the parts connected with said lever, to effect lowering of the "man speed dogs" or shoes 24 and to effect release of the levers 26 from the suspending links 50, causing said levers to be supported by their shoes 34 and the tracks 35 so that at the proper time, said tracks may permit the levers 26 to drop, lowering the actuators 15, for the purpose hereinbefore described.

It will be seen from the foregoing that distinct improvements have been made over the safety mine hoists heretofore in existence. Moreover, it will be clear to those skilled in the art that while certain specific features of construction and relation of parts have been disclosed for carrying out the desired ends, the invention is subject to numerous modifications. Hence, the present disclosure is to be considered primarily as illustrative, rather than limiting.

We claim:

1. In a safety mine hoist having a control member to effect hoist-stopping, an actuator for said control member normally spaced from the latter, speed-responsive means for moving said actuator toward said control member proportionately with hoist speed increase, and means for automatically moving said control member toward said actuator during the near-landing movement of the hoist; means independent of said speed responsive means for moving said actuator toward said control member to a predetermined position during the aforesaid near-landing movement.

2. In a safety mine hoist having a control member to effect hoist-stopping, an actuator for said control member normally spaced from the latter, speed-responsive means for moving said actuator toward said control member proportionately with hoist speed increase, and means for automatically moving said control member toward said actuator during the near-landing movement of the hoist; means independent of said speed-responsive means for automatically moving said actuator toward said control member to a predetermined position during the aforesaid near-landing movement.

3. In a safety mine hoist having a control member to effect hoist-stopping, an actuator for said control member, speed-responsive means for moving said actuator toward said control member proportionately with hoist speed increase, and means, embodying a driven table, for automatically moving said control member toward said actuator during the landing-approaching movement of the

hoist; means independent of said speed-responsive means for moving said actuator toward said control member to a predetermined position, and means governed by the aforesaid table for bringing said independent actuator-moving means into play when the near-landing movement of the hoist takes place.

4. In a safety mine hoist having a control member to effect hoist-stopping, an actuator for said control member, speed-responsive means for moving said actuator toward said control member proportionately with hoist speed increase, and means, embodying a driven table, for automatically moving said control member toward said actuator during the landing-approaching movement of the hoist; means independent of said speed-responsive means for moving said actuator toward said control member to a predetermined position, and means, embodying a track on said table, for holding said independent actuator-moving means against action until the near-landing movement of the hoist takes place.

5. In a safety mine hoist having a control member to effect hoist-stopping, an actuator for said control member, speed-responsive means for moving said actuator toward said control member proportionately with hoist speed increase, and means, embodying a driven table, for automatically moving said control member toward said actuator during the landing-approaching movement of the hoist; a lever operatively connected with said actuator and provided with means urging it in a direction to shift the actuator toward the control member, a shoe carried by said lever, and a track carried by the aforesaid table and engageable with said shoe to hold said lever against movement under the influence of said urging means until the near-landing movement of the hoist takes place.

6. In a safety mine hoist having a control member to effect hoist-stopping, an actuator for said control member, speed responsive means for moving said actuator toward said control member proportionately with hoist speed increase, and means for moving said control member toward said actuator during near-landing movement of the hoist; means independent of said speed-responsive means for moving said actuator toward said control member during said near-landing movement of the hoist, and means for simultaneously placing said control-member-moving-means and said independent actuator-moving means in condition to function.

7. In a safety mine hoist having a control member to effect hoist-stopping, an actuator for said control member, speed-responsive means for moving said actuator toward said control member proportionately with hoist speed increase, and means, em-

- bodying a driven table, for automatically moving said control member toward said actuator during the landing-approaching movement of the hoist; a lever connected with said actuator and provided with means urging it to move in a direction to shift the actuator toward the control member, a shoe carried by said lever, a track carried by said table for engagement with said shoe to hold said lever against movement under the influence of said urging means until the near-landing movement of the hoist takes place, and means for placing the aforesaid control-member-moving-means in condition to function and for simultaneously placing said shoe in co-operative relation with said track.
8. In a safety mine hoist having a control member to effect hoist-stopping, an actuator for said control member, speed-responsive means for moving said actuator toward said control member proportionately with hoist speed increase, a lever connected with said control member and having a movably mounted shoe, and a driven table having a cam co-operable with said shoe for moving the lever to shift the control member toward the actuator during the near-landing movement of the hoist; means independent of said speed-responsive means for moving said actuator toward said control member, means embodying a track on the aforesaid table and a coacting shoe, for holding said independent actuator-moving means against action until the near-landing movement of the hoist takes place, and means for simultaneously disposing the first named shoe in the path of its co-operating cam and placing the second named shoe in co-operative relation with the aforesaid track.
9. In a safety mine hoist having a control member to effect hoist-stopping, an actuator for said control member, speed-responsive means for moving said actuator toward said control member proportionately with hoist speed increase, a lever connected with said control member and having a movably mounted shoe, and a driven table having a cam co-operable with said shoe for moving the lever to shift the control member toward the actuator during the near-landing movement of the hoist; a second lever connected operatively with the actuator and provided with means urging it to move in a direction to shift said actuator toward the control member, a second shoe on said second lever, a track on the aforesaid table to engage said second shoe and hold said second lever against action until near-landing movement of the hoist takes place, and means for simultaneously disposing the first named shoe in the path of its co-operating cam and disposing the second shoe in co-operative relation with said track.
10. In a safety mine hoist having a control member to effect hoist-stopping, an actuator for said control member, speed-responsive means for moving said actuator toward said control member proportionately with hoist speed increase, a lever connected with said control member and having a movably mounted shoe, and a driven table having a cam co-operable with said shoe for moving the lever to shift the control member toward the actuator during the near-landing movement of the hoist; a second lever connected operatively with the actuator and provided with means urging it to move in a direction to shift said actuator toward the control member, a second shoe on said second lever, a track on the aforesaid table to engage said second shoe and hold said second lever against action until near-landing movement of the hoist takes place, a bell crank having operative connection with the first named shoe for disposing it in the path of its co-operating cam, and suspending means connected to said bell crank, said suspending means supporting said second lever in an inoperative position but serving to free the same and place it under control of its shoe and the coacting track when the bell crank is moved to dispose the first named shoe in the path of its co-operating cam.

In testimony whereof we have hereunto affixed our signatures.

THOMAS R. COOK.
DONALD N. SMITH.
